UNITED STATES PATENT OFFICE

2,499,940

POULTRY FOUNTAIN

Jacob A. Albert, Annville, Pa.

Application November 24, 1945; Serial No. 630,571

1. Claim. (Cl. 137—68)

1

The present invention relates to new and useful improvements in poultry fountains and more particularly to a device of this character which will automatically maintain a supply of water in the fountain.

An important object of the present invention is to provide a device of this character in which an inner drinking basin is suspended by spring means within an overflow basin whereby water dripped by the poultry while drinking from the inner basin will be caught in the overflow basin and drained from the fountain without resulting in a wetting of the ground surrounding the fountain.

A further object of the invention is to provide a control valve supported on the drinking basin and normally held in open position by spring suspension means for the inner basin, the weight of water entering the drinking basin serving to automatically close the valve.

A further object of the invention is to provide an apparatus of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view.

Figure 2 is a top plan view.

Figure 3 is a longitudinal sectional view taken substantially on a line 3—3 of Figure 2.

Figure 4 is a transverse sectional view taken on a line 4—4 of Figure 1.

Figure 5 is a perspective view of the adjustable plate for the spring suspension means, and

Figure 6 is an enlarged fragmentary sectional view taken substantially on a line 6—6 of Figure 2.

Referring now to the drawings in detail wherein for the purpose of illustration I have disclosed a preferred embodiment of the invention, the numeral 5 designates an open drinking basin and the numeral 6 designates an open drip basin, the basins being of predetermined shape and the drinking basin 5 being of an area less than the area of the basin 6 and arranged with the drinking basin within the drip basin.

The inner surface of the drip basin 6, at one side thereof is formed with one or more recesses 7 having a pin 8 extending transversely thereof

2

and spaced from the recess for engagement by a rigid hook 9 projecting outwardly from one side of the drinking basin 5 whereby to pivotally support one side of the drinking basin in spaced relation from the walls and bottom of the drip basin 6 as will be apparent from an inspection of Figures 3 and 4 of the drawings. The pin 8 may be secured in place by having its ends imbedded in the inner wall of said basin 6.

10 The other side of the drip basin 6 is formed with a boss 10 having a vertical water passage 11 formed therein and connected at its lower end to a conventional form of valve 12 in a supply pipe 13, the upper end of the passage 11 having a pipe 14 connected thereto and rising from the rear edge of the drip basin.

A valve housing or body 15 is connected to the upper end of the pipe 14 by means of an elbow 16 so that the valve body 15 overlies the drinking basin 5.

15 The bottom of the valve body 15 is formed with a valve seat 17 adapted for engagement by a conical valve 18 carried at the upper end of a valve stem 19 which extends downwardly through 20 the bottom of the valve body 15 and through a tubular guide 20 connected to the bottom of the valve body. The stem 19 is of a diameter substantially less than the internal diameter of the guide 20 whereby water from the valve body 15 25 is adapted to freely pass through the guide 20 for discharge into the drinking basin 5. The lower end of the valve stem 19 is adapted to rest upon the bottom of the drinking basin 5 as will be apparent from an inspection of Figure 3 of the drawings.

30 The rear end of the drinking basin 5 is supported in an elevated position above the bottom of the drip basin 6 by means of an expandable coil spring 21 connected at its lower end to the drinking basin and having a hook 22 at its upper end adapted for selective engagement in inclined rows of keyhole slots 23 formed in a connecting plate 24. The upper end of the connecting plate is supported between the elbow 16 and valve body 45 15 by means of a wire hanger 25.

The bottom of the drip basin 6 is provided with a drain pipe 26.

40 In the operation of the device the lower end of the spring 21 is adjusted in the keyhole slots 50 23 of the connecting plate 24 so that the lower end of the valve stem 19 will be raised upwardly by the drinking basin 5 to maintain the valve 18 in an open position, as shown in Figure 3 of the drawings. Upon opening the valve 12 water will then enter the drinking basin 5 through the tubu-

lar guide 20 and the weight of the water after reaching a predetermined level will lower the drinking basin against the tension of the spring 21 and the valve 18 will gravitate into closed position.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

What is claimed is:

A poultry fountain comprising a drip basin, an elongated drinking basin pivoted at one end in the drip basin for downward swinging under the weight of liquid therein, means adjustably suspending the drinking basin at the other end thereof and yieldingly urging said other end upwardly, a liquid supply pipe line having a discharge end overlying the suspended end of said drinking basin, and a downwardly closing valve in said discharge end of said pipe including a

valve operating rod resting at one end on the bottom of said drinking basin at said suspended end thereof for upward and downward movement with said drinking basin to open and close said valve respectively, said means comprising a suspended plate with transverse inclined rows of openings therein, and a coil spring pivoted to the drinking basin and having a hook end for hooking into said openings selectively.

JACOB A. ALBERT.
